SNOW-REMOVING DEVICE

John Gehl, Denmark, Wis.

Application April 8, 1937, Serial No. 135,716

1 Claim. (Cl. 37—43)

This invention appertains to snow removing devices, and more particularly to a power-driven rotary snow removing machine.

One of the primary objects of my invention is to provide a snow removing machine having means for scraping up the snow, and novel means operated from the engine of the pushing vehicle for blowing the snow to one side or the other of the machine and completely out of the path of the machine, whereby to effectively reduce the strain on the machine and to permit the rapid handling of the snow.

Another salient object of my invention is to provide a pushing vehicle, such as a tractor, with a snow removing device thereon, embodying a casing arranged transversely of the machine having an open front portion or mouth carrying a scraper blade for directing the snow into said mouth, and a rotary blower in said casing for breaking up the snow and for throwing the snow through a blower pipe, which can be directed to either side of the machine, as may be desired.

A further object of my invention is to provide a machine of the above character, which can be compactly built, whereby the same can be effectively used for cleaning sidewalks and the like.

A still further object of my invention is to provide a sidewalk snow removing machine including a small tractor, carrying the snow removing device, having side endless crawler belts and a guide handle having the various controlling devices thereon, whereby the movement of the belts and the operation of the snow removing device can be conveniently manipulated by the operator.

With these and other objects in view the invention consists in the novel construction, arrangement, and formation of parts, as will be hereinafter more specifically described, claimed, and illustrated in the accompanying drawings, in which drawings:

Figure 1 is a side elevation of the improved machine for removing snow from sidewalks, crosswalks, and the like, parts of the view being shown broken away and in section.

Figure 2 is a top plan view of the machine for removing snow from sidewalks, parts of this view being also shown broken away and in section.

Figure 3 is an enlarged, detail sectional view taken substantially on the line 3—3 of Figure 1, illustrating a preferred drive arrangement.

Figure 4 is a fragmentary, side elevation view, with parts thereof broken away and in section, showing my snow removing device mounted upon a large or riding tractor.

Figure 5 is a detail, transverse sectional view taken on the line 5—5 of Figure 4, illustrating a part of the adjusting mechanism for the snow removing device.

Referring to the drawings in detail, wherein similar reference characters designate corresponding parts throughout the several views, the letter S generally indicates my snow removing machine, which has been particularly designed for clearing long stretches of sidewalks and the like.

As illustrated, the machine includes a frame 10 having mounted thereon any preferred type of internal combustion engine 11. This engine is employed for driving the side endless crawler belts 12 and 13, and this drive mechanism and the controls therefor will be more fully set forth.

A rotatable stub shaft 14 is disposed at one side of the engine crank-shaft 15 and is operatively connected thereto by means of a clutch 16. This clutch is adapted to be operated through the medium of a hand lever 17 mounted upon the operating handle 18. The hand lever 17 has operatively connected thereto an actuating link 19, which leads to and operates the movable section 25 of the clutch.

Keyed or otherwise secured to the stub shaft 14 is a pair of spaced sprocket wheels 21 and 22. The sprocket wheel 21 is utilized for driving the jack shaft 23, and the jack shaft can have 30 mounted thereon a relatively large sprocket wheel 24. A drive sprocket chain is trained over the sprocket wheels 21 and 24. The jack shaft is utilized for operating the crawler tracks or belts, and the opposite ends of the jack shaft 35 are operatively connected through the medium of clutches 25 and 26 with stub shafts 27 and 28. These stub shafts 27 and 28 are operatively connected to the drive axles 29 of the crawler tracks or belts.

As illustrated, the stub shafts 27 and 28 have keyed or otherwise secured thereto sprocket wheels 30, and these sprocket wheels receive drive sprocket chains which are trained about sprocket wheels 31 secured to the axles 29 of 45 said crawler belts. The controls for the clutches 25 and 26 are also mounted upon the handle 18, whereby these clutches can also be conveniently manipulated by the operator. As shown, the handle 18 carries rotatable hand grips 32.

Each of these hand grips has formed thereon or secured thereto a crank lever 33 for manipulating links 34. These links 34 lead to their respective clutches 25 and 26, and by turning the hand grips the movable clutch sections of the 55

5   clutches 25 and 26 can be manipulated. If so desired, the movable sections of the clutches can be normally held out of engagement by springs, so that upon the release of the hand grips the 10   clutches will be automatically disengaged. By manipulating the hand grips, both of the tractor belts or crawler treads can be operated in unison, or one or the other can be thrown out so that the tractor can be guided and turned around.

10   Rigidly mounted upon the frame 10 of the tractor is a pair of forwardly extending brackets 34 to which is rigidly secured a substantially U-shaped supporting frame 35. Mounted upon the arms of the frame is a substantially cylindrical casing 36, and the front lower end of the casing is left open to form an entrance mouth for the snow. The upper forward end of the casing can be provided with a hinged cover 37. A scraper blade 38 is carried by the lower edge of the casing for 15   engaging and scraping the snow from the ground, and, if desired, this blade can be resiliently mounted.

15   20   Arranged within the casing 37 is a rotary snow blower or elevator 39. This blower 39 preferably includes end hubs 40 rigidly mounted upon an axle shaft 41. The ends of the axle shaft are mounted in suitable bearings carried by the casing and the arms of the U-shaped bracket 35. The hubs 40 are connected by spiral blower blades 30   42, which serve to break up and cut through the snow scraped up by the scraper blade 38, and for carrying and blowing the snow to one side of the machine and the sidewalk.

20   25   The upper end of the casing 36 terminates in a dome 43, which may be provided with snow guiding vanes, and the upper end of the dome has rotatably mounted thereon a blower pipe 44. This blower pipe can be swung in any direction desired so that the snow can be blown to either side of the machine as may be desired.

25   30   35   From the foregoing description it can be seen that I have provided an exceptionally simple and compact form of snow removing device, which can be effectively used on sidewalks for permitting the quick removal of snow therefrom.

30   35   40   The sprocket wheel 22 on the stub shaft 14 has trained about the same a sprocket chain 45, which leads about a sprocket wheel 46 carried or otherwise secured to the axle shaft 41 of the blower. Hence, it can be seen that the blower is operated 45   50   from the engine 11 of the tractor.

35   40   45   When the clutch 16 is thrown out by the operator, the blower as well as the machine can be instantly brought to a halt, and by leaving the clutch 16 thrown in and by throwing out the clutches 25 and 26 the blower can be actuated, and the tractor can be brought to a standstill. This is advantageous in the initial starting of the machine and in handling relatively large snow-drifts.

40   45   50   While in Figures 1 to 3 inclusive I have shown the principles of my snow removing device applied to a relatively small walking tractor, whereby the machine can be used on sidewalks, it is to be understood that the snow removing device can be effectively used on large tractors for roadwork.

45   50   55   In Figures 4 and 5 I have illustrated my snow removing device mounted upon a large or riding tractor. The letter T generally indicates the tractor in these figures, and D the snow removing device.

50   55   60   The tractor can be of any preferred size or make, and only sufficient parts thereof have been illustrated to show one means of mounting the snow removing device thereon.

60   65   70   As illustrated in Figures 4 and 5, the tractor T includes a frame having a rear axle 50 and a front axle 51. A suitable engine 52 is mounted on the frame, and the crankshaft 53 extends slightly in advance of the axle 51. The snow removing device D includes a pair of longitudinally extending supporting side beams 54, and the forward ends of the beams have rigidly secured thereto a U-shaped supporting member 55 in which is secured the transversely extending substantially cylindrical casing 56.

70   75   80   The front end of the casing is left open and the rear end of the casing carries the scraper blade 57. The upper end of the casing terminates in a dome 58 on which is rotatably mounted a blower pipe 59. The blower pipe 59 can be provided with an annular worm gear 60 with which meshes a worm 61. This worm is rigidly secured on an operating shaft 62 rotatably mounted in suitable bearings. The shaft extends 85   90   95   rearwardly of the tractor toward the operator's seat.

90   95   100   The supporting beams 54 adjacent to their rear ends are rockably mounted on the rear axle 50, and the beams can be provided with U-shaped bolts 63 for engaging about the axle. If desired, depending U-shaped guides 64 can be connected to the front axle 51 for guiding the swinging movement of the supporting beams. By raising and lowering the supporting beams, the position 105   110   115   of the scraping blade 57 relative to the ground can be adjusted.

110   115   120   Any preferred means can be provided for raising and lowering the beams, and, as shown, I provide a cross-shaft 65 rotatably mounted on the tractor, the terminals of which carry beveled gears 66 for meshing engagement with beveled gears 67 keyed or otherwise secured to screws 68. These screws 68 have traveling nuts 69 mounted thereon, and the nuts are connected by means of pins 70 to the beams 54. The cross-shaft 65 can be turned in any desired manner to bring about the raising and lowering of the beams. As shown, a worm wheel 71 is keyed to the cross-shaft, and the worm wheel has meshing therewith a worm 72, which is keyed or otherwise secured to a rotatable shaft 73. This shaft can lead back to a point adjacent to the driver's seat, so that the driver can readily manipulate the same.

120   125   130   The casing 56 has mounted therein a rotary blower 74, which is of substantially the same type of blower as that shown in Figures 1 and 2, and this blower is adapted to be operated from the engine 52 of the tractor. An operating drive shaft 75 is provided, and the forward end of this shaft is operatively connected to the blower in any desired manner, such as through the medium of meshing beveled gears. The shaft 75 is operatively connected to the engine crankshaft through the medium of a clutch 76 and universal joint 77. Means is also provided for permitting the operation of the clutch by the driver of the vehicle, whereby the rotation of the blower 74 can be controlled.

130   135   140   While in both forms of my invention I have shown the rotary blower mounted in a horizontal plane, it is to be understood that I do not wish to restrict myself to the exact position of this blower, as obviously the same could be mounted at an angle to the horizontal. Likewise, the rotary blower can take other shapes and forms.

140   145   150   Other changes in details may be made with-

out departing from the spirit or the scope of my invention, but what I claim as new is:

5 In a machine for removing snow from sidewalks, a rigid frame, an engine mounted directly on said frame, ground-engaging means carried by the opposite sides of the frame driven from said engine, a rearwardly extending manipulating handle on the frame, brackets on the front end of the frame projecting forwardly in spaced parallel relation, a forwardly and downwardly 10 extending U-shaped support secured to the brackets and arranged transversely of the frame

and in front of the ground-engaging means, a cylindrical casing secured to the U-shaped support having an entrance mouth, a scraper blade on the casing, a blower pipe communicating with the casing, a rotary blower mounted within the casing above the scraper including a transversely extending shaft rotatably mounted in the casing and in the forward ends of the U-shaped support, and means for rotating the shaft from the engine.

10 JOHN GEHL.
